UNITED STATES PATENT OFFICE.

JOHN BLAKELY, OF BROOKLYN, NEW YORK.

KNOCKDOWN BOX.

SPECIFICATION forming part of Letters Patent No. 291,281, dated January 1, 1884.

Application filed November 16, 1883. (No model.)

To all whom it may concern:

Be it known that I, JOHN BLAKELY, a citizen of the United States, residing in the city of Brooklyn, county of Kings, and State of New York, have invented certain new and useful Improvements in Knockdown Boxes, fully described and represented in the following specification and the accompanying drawings, forming a part of the same.

10 The present invention relates to what are known as "knockdown" boxes—that is to say, that class of boxes which are capable of being bent into a flat form for storage or shipment and again restored to box form when required for use.

15 It is the object of the invention to provide a simple and inexpensive box of this character which shall be especially adapted for use in sending samples of merchandise through the mails, for which purpose a box or package is required which can be closed so as to securely hold the contents and yet be capable of being opened and reclosed as often as may be desired to permit an inspection of the contents by the post-office officials.

20 To these ends the invention consists in a knockdown box having the peculiarities of construction which will be hereinafter fully explained and particularly pointed out.

25 In the accompanying drawings, Figure 1 is a plan view of the blank from which the box is made; Fig. 2, a perspective view of the box with one of its ends closed and the other open; Fig. 3, a like view of the box, showing one of its ends closed and the other partially closed; Fig. 4, a cross-section taken upon the line $z z$ of Fig. 3; Fig. 5, a partial section, upon an enlarged scale, taken upon the line $x x$ of the same figure, the parts being in position to entirely close the end of the box; and Fig. 6, a like view taken upon the line $v v$ of the same figure, the parts being in the same position as in Fig. 4.

30 Referring to Fig. 1, it will be seen that the box is made from a single sheet or blank, which is of rectangular form, and is provided upon one side with a flap 2, and upon two opposite sides with tongues 3. The blank thus formed is provided with cuts $a b c$, extending inward from two of its sides, so as to form the end-closing portions 5 6 7 8 upon opposite sides of the blank, and is creased, scored, or

35 indented upon the lines $g g$, $h h$, $i i$, $k k$, $g m$, and $g n$, so as to define the lines of fold between the side and edge forming portions 9 55 10 11 12, and between these portions and the end-forming portions 5 6 7 8. The blank is also provided upon the lines $g h$, which form the fold-lines between the end-forming portions 5 and the side-forming portion 9, with 60 cuts r , which are of a length about equal to the width of the tongues 3, and are adapted to receive said tongues when the box is closed. The tongues 3, it will be observed, extend from the end-forming portions 7, which are attached 65 to the opposite side-forming portion 10 of the box, so that when the parts are folded down in the act of closing the box these tongues are in proper position to enter the cuts r and lock the ends of the box. In forming the box the 70 blank is first folded upon the lines $g g$, $h h$, $i i$, and $k k$, so as to assume the tubular form shown in Fig. 2, and cause the flap 2 and edge-forming portion 12 to overlap each other, as shown in Fig. 4, after which the parts 2 75 12 are cemented or otherwise secured to each other. When the box is in this condition, it can be "knocked down" for storage or shipment by simply pressing either two of its diagonally-opposite corners inward, so as to cause one 80 of the side and one of the edge forming portions to lie flat upon the opposite side and edge forming portions. When the box is required for use, all that is necessary is to restore it to the tubular form, as shown in Fig. 85 2, insert the contents, and close the ends. This last is accomplished by folding the parts 6 8 inward, so that their ends will lie adjacent to each other, as shown in Fig. 5, then folding the parts 5 over onto the parts 6 8, as shown 90 in Figs. 5 and 6, and, finally, folding the parts 7 over onto the parts 5, and inserting the locking-tongues 3 into the cuts r , as shown in Figs. 3 and 5. By this means the ends of the box are securely closed without cementing or 95 otherwise permanently fastening the parts together, so that by simply withdrawing one or both of the tongues 3 and raising the parts 5 6 7 8 the contents of the box can be inspected from one or both ends and the box reclosed as 100 often as may be desired, thus making the box especially well adapted for use in transporting samples of merchandise through the mails.

What I claim is—

The herein-described knockdown box, consisting of a tubular body provided at its ends with closing portions 5 6 7 8, one of said portions being provided with a locking-tongue, 5 as 3, and the opposite portion with a cut, as 7, located upon the fold-line between said portion and the body of the box, substantially as described.

In testimony whereof I have hereunto set my hand in the presence of two subscribing 10 witnesses.

JOHN BLAKELY.
